US00D958137S

(12) **United States Design Patent** (10) **Patent No.:** **US D958,137 S**
(45) **Date of Patent:** **** Jul. 19, 2022**

(54) **WEARABLE DEVICE**

- (71) Applicant: **Apple Inc.**, Cupertino, CA (US)
- (72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

- (73) Assignee: **Apple Inc.**, Cupertino, CA (US)

- (**) Term: **15 Years**

- (21) Appl. No.: **29/796,672**

- (22) Filed: **Jun. 25, 2021**

Related U.S. Application Data

- (63) Continuation of application No. 29/733,250, filed on Apr. 30, 2020, now Pat. No. Des. 923,622, which is a continuation of application No. 29/662,900, filed on Sep. 10, 2018, now Pat. No. Des. 883,976, which is a continuation of application No. 29/615,074, filed on

Aug. 25, 2017, now Pat. No. Des. 828,352, which is a continuation of application No. 29/583,454, filed on Nov. 4, 2016, now Pat. No. Des. 795,864, which is a continuation of application No. 29/499,082, filed on Aug. 11, 2014, now Pat. No. Des. 771,036.

(57) **CLAIM**

The ornamental design for a wearable device, as shown and described.

DESCRIPTION

FIG. 1 is a front view of a wearable device showing the claimed design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The oblique shade lines in the figures show transparency or translucency.

The broken lines in the figures show portions of the wearable device that form no part of the claimed design.
